FIG. 2

INVENTOR:
ALBERT L. ARENBERG,

BY Cheever & Cox

ATTYS.

UNITED STATES PATENT OFFICE.

ALBERT L. ARENBERG, OF CHICAGO, ILLINOIS.

REFLECTOR.

1,407,910.

Specification of Letters Patent. Patented Feb. 28, 1922.

Application filed January 10, 1920. Serial No. 350,523.

To all whom it may concern:

Be it known that I, ALBERT L. ARENBERG, a citizen of the United States, residing at Chicago, in the county of Cook and State of Illinois, have invented a certain new and useful Improvement in Reflectors, of which the following is a specification.

My invention relates to reflectors more particularly for commercial and industrial 10 lighting, and the object of the invention is to provide simple and inexpensive means whereby the great bulk of the light rays emanating from the lamp bulb will be thrown downward and outward but a small 15 portion will be thrown outward and upward to illuminate the ceiling to a moderate extent and thus improve the appearance and cheerfulness of the room.

I obtain my object by the construction 20 illustrated in the accompanying drawings in which—

Figure 1 is a central vertical section of a reflector embodying my invention, and

Figure 2 is a top plan view of approximately one-half of the reflector showing the construction at the periphery thereof.

Like numerals denote like parts throughout the several views.

In the particular form selected to illustrate the invention the reflector has four main zones or divisions, viz., a main domelike portion 1, a trunco conical stem 2 surmounting the domelike portion, an annular apron 3 joined to and descending from the 35 lower rim of the domelike portion 1, and an annular flange 4 which joins the lower rim 5 of the apron and extends outward and slightly upward. The frusto conical portion 2 is well adapted to house a lamp receptacle 40 or socket 6 for supporting and energizing an electric lamp bulb 7. It is also desirable that the portion 2 have an opening 10 at the top to accommodate a stem 11 or other fixture element by which the reflector is supported 45 and the supply conductors (not shown) housed.

A row of apertures 12 is formed near the bottom of the portion 3, these apertures being arranged symmetrically in a horizontal 50 ring and so placed that the light rays emanating from the filament 14 of the lamp bulb will pass through said apertures, impinging upon the upper surface of the flange 4 and be reflected by said flange upward and outward 55 as indicated in the dotted lines in Figure 1.

It is desirable, although not essential, to form a beading 15 at the outer rim of the flange 4. This not only imparts a finished appearance to the device as a whole and strengthens it, but renders it more certain 60 that no light rays passing through the apertures 12 will be visible to the eye of an observer standing at any point below the level of the device. As a practical matter, it is desirable that the entire reflector be white 65 enameled both inside and outside, thus promoting its reflective properties both as to the rays which strike the underside of the reflector and also as to those which pass out through the openings 12 and strike the upper surface of the flange 4.

In use, when the lamp is energized by far the major portion of the rays, except those which pass directly to a point below the lower rim, will strike the underside of 75 the reflector and be diffused in a manner depending upon the precise configuration of the reflector and the particular location of the lamp filament with respect to it. A small portion of the rays, however, will pass 80 out through the openings 12 and impinge upon the upper surface of the flange 4. The rays which thus pass through these apertures will be reflected upward and outward and be diffused in such manner as to produce a soft and pleasant lighting effect upon 85 the ceiling above. The rays thus passing through the apertures will not be of any particular value in illuminating the parts directly beneath, but they are none the less 90 valuable in promoting the general lighting effect which prevents the formation of dark shadows above a fixture. Reflectors are usually located not very far below the ceiling and hence are considerably above the 95 level of the eyes of persons standing or sitting in the room. Under these conditions with my device the observer will not obtain direct vision of the light rays which pass out through the apertures. Such observer 100 will, however, see the apertures from the lower side of the reflector and when the apertures are symmetrically formed and placed, as typified in the accompanying drawings, they constitute a decoration in 105 themselves and add an unusual and attractive appearance to the installation as a whole.

It will be understood, of course, that the configuration of the portion comprised 110

within the zones 1, 2, and 3 may be considerably varied without departing from the spirit of the invention, the underlying principle of the invention being pointed out in 5 the appended claims.

Having thus described my invention what I claim as new and desire to secure by Letters Patent, is:

1. A concave reflector adapted to contain 10 a source of light on its concave side, the rim at the mouth of the reflector being in a plane at right angles to the axis, and a flange bordering the rim and extending approximately radially outward therefrom, the reflector having apertures behind the plane 15 of the rim whereby the light passing through them from the internal light source may strike the back surface of the flange.
2. A concave reflector adapted to contain 20 a source of light behind the plane of its mouth, an annular flange formed at the mouth of the reflector, said flange being oblique to the axis of the reflector and projecting obliquely backward from the mouth 25 of the reflector, the body of the reflector being apertured near to but behind the point where the flange joins the body of the reflector whereby the rays emanating from the source of light will pass through the aper-

tures and strike the back surface of the 30 flange.

3. A concave reflector having a flange extending upward and outward from its lower margin, means for suspending a source of light at the central axis of the reflector and 35 slightly above the lower edge thereof, the reflector having a row of apertures in the concave portion near but slightly above the lower edge whereby the light rays passing from said source out through said aperture 40 impinge upon the upper surface of said flange.

4. A concave reflector having a flaring open mouth, the rim whereof is at right angles to the axis of the device, and is 45 adapted to lie in a horizontal plane, a source of light located chiefly above the plane of the rim substantially at the axis, the reflector having apertures near the lower rim 50 of the reflector, and an annular flange having reflecting properties and extending outward and upward from the rim whereby the light rays passing through the apertures will strike the top of the flange and be reflected upward.

In witness whereof, I have hereunto subscribed my name.

ALBERT L. ARENBERG.
